UNITED STATES PATENT OFFICE

CORA A. PRICE, OF SUNBURY, PENNSYLVANIA

WORK GUIDE FOR SEWING MACHINES

Application filed July 29, 1929. Serial No. 381,871.

This invention relates to a guide for sewing machines whereby the work being sewed can be held in proper position relative to the needle.

5 It is an object of the invention to combine a novel form of guide with the presser-foot of the sewing machine, this guide being maintained movably in the bottom plate so that it is not possible for the work to shift laterally when the presser-foot is raised.

With the foregoing and other objects in view which will appear as the description proceeds, the invention resides in the combination and arrangement of parts and in 15 the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

25 Figure 1 is a side elevation of the presser-foot of a sewing machine provided with a guide shield.

Figure 2 is a bottom plan view thereof.

Figure 3 is a section on line 3—3, Figure 1.

30 Figure 4 is a plan view of the plate that cooperates with the guide.

Referring to the figures by characters of reference, 1 designates the presser-foot of a sewing machine forked as at 2 to permit free movement of the needle. Secured to or formed with one side of the presser-foot is an arcuate guide plate 3 having its convex side nearest the presser-foot so that the ends of the guide plate curve away from the line 40 along which a fabric is to be sewed.

Arranged beneath the presser-foot is the usual base plate 4 adapted to overlie the shuttle and having the usual slots 5 within which the needle and the feeding mechanism will work. Another arcuate slot 6 is also formed in this plate and is so shaped and proportioned as to receive the lower edge portion of the guide plate 3 which, as shown in Figures 1 and 3, is extended well below the bottom surface of the presser-foot.

When the presser-foot is raised, the guide plate 3 will be raised therewith but will not be withdrawn from its slot 6. Thus the fabric to be sewed can be placed under the presser-foot and shifted laterally until it touches the guide plate. It cannot pass under this guide plate. Thereafter the presser-foot is lowered and the guide plate will move downwardly in its slot 6.

With the parts thus positioned the stitching operation can be performed and the guide plate will of course be of great value as a means for insuring proper spacing of the line of stitches from the edge of the garment or fabric being sewed.

It has been found that this presser-foot with a guide and base plate such as described is especially advantageous in sewing collars, cuffs, and the like.

By extending the arcuate guide plate 3 into a slot in which it is seated at all times during the sewing operation, said plate can be made of relatively thin material without danger of being sprung laterally by the fabric being sewed even though said fabric should be very heavy.

What is claimed is:

The combination with the presser-foot of a sewing machine, of an arcuate guide at one side of and carried by the presser-foot, said guide being bowed in the direction of its length and having its convex face nearest the presser-foot, the lower portion of the guide being extended below the presser-foot, and a base plate extending under and cooperating with the presser-foot, said plate having an arcuate slot in which the guide is seated while the presser-foot is in raised or in lowered position the walls of the slot constituting means for holding the guide against lateral displacement when subject to pressure from a fabric being sewed.

In testimony that I claim the foregoing as my own, I have hereto affixed my signature.

CORA A. PRICE.
